UNITED STATES PATENT OFFICE.

PATRICK CHURCHILL, OF MANCHESTER, ENGLAND.

BUOYANT LIFE-SAVING FITTING AND APPLIANCE FOR SHIPS.

1,359,152.

Specification of Letters Patent. Patented Nov. 16, 1920.

Application filed October 25, 1919. Serial No. 333,294.

To all whom it may concern:

Be it known that I, PATRICK CHURCHILL, a subject of the King of Great Britain, residing at Manchester, in the county of Lancaster, England, have invented certain useful Improvements in Buoyant Life-Saving Fittings and Appliances for Ships, of which the following is a specification.

This invention relates to improvements in that type of fittings or appliances employed in connection with ship deck houses or cabins, which in case of shipwreck can be occupied by persons on board and detached from the deck to allow it to float on the water and thereby save life.

The invention has for its object to improve said type of fittings or appliances to permit a more ready and rapid detachment of said house or cabin from the deck, when required to float on the water.

A deck house or cabin fitting or appliance of said type according to this invention comprises chiefly a series of screw-threaded rotary spindles extending through each end wall of deck house or cabin in the direction of the ship side bulwarks and the inner ends of which are each provided with a hand wheel or other suitable rotating gear and the outer end adapted to engage in sockets secured to the inner side of the bulwarks or to a part of the deck secured adjacent to said end walls, whereby said house or cabin can be readily secured to bulwark or deck, and in case of necessity rapidly detached therefrom for floating on the water.

I obtain this object by the means illustrated in the accompanying drawing—

Figures 1 and 2 are respectively a side view and end view of a ship having a cabin or room secured to the deck thereof in accordance with this invention.

Figs. 3 and 4 are respectively on an enlarged scale, a detached sectional side view and plan of the cabin attaching and releasing means.

Figs. 5, 6 and 7 are sectional views of two modifications of the attaching and releasing means.

Figs. 8 and 9 are respectively a sectional end view and side view and Fig. 10 a side view showing the invention applied to such as a chart or wireless room on the deck of the ship.

Similar letters refer to similar parts throughout the several views.

Referring to Figs. 1, 2, 3 and 4, *a* is said

cabin or room which extends across the whole width of the deck and comprises a bottom *b* which may be formed hollow to serve as a water tank, four sides two of which may be slanting and a ceiling the outside of which is provided with railings and serves as a deck rendered accessible from the ordinary deck by means of a ladder or stairs and provided with a companion-way entrance and stairs reaching down to the floor of the house or cabin.

g are a series of brackets, secured to the inner sides of the house or cabin walls adjacent to the bulwark of the ship and have mounted therein the said screw-threaded spindles *e* each provided with a hand wheel *h*.

Each inner side of the bulwark *c* is furnished with a series of sockets *i* in which the free end of said spindles *e* are adapted to engage and lock the cabin or room to the bulwark *c* and thus prevent same from lifting off the deck *d*.

Above the brackets *g* are secured to the inside of the cabin or room end another series of brackets *k* in each of which is also mounted a screw-threaded spindle *f* having a hand wheel *m*.

The outer end of each of these spindles *f* has connected therewith a swivel *n* secured to the inside of a plate *o* hinged to the outside of the cabin or room at *p* and overlapping the outside of the bulwark *c*.

The swivel spindles *f* are adapted to draw the said hinged plates *o* tightly against the plates *q* secured to the ship's side and thereby securely lock the cabin or room laterally in position on the deck.

By unscrewing the said spindles the cabin or room can be instantly released from the deck, and thus floated.

Figs. 8, 9 and 10 show a cabin or room such as a chart or wireless room, having a single series of spindles engaging in sockets formed in angle pieces or rails 13 secured to the deck with spindles operated from the top.

To the top of the cabin or room *a* is secured, a support 6 in which is mounted a shaft provided at each end with a hand wheel 8 and in the middle with a chain wheel which by means of an endless chain 10 is connected with a chain wheel 11 secured on said cross shaft 4.

It will thus be seen that said cabin or room may be locked to the deck and bulwark

or released therefrom either from the top or the interior thereof by rotating the chain wheel by means of the hand wheel *m* or the chain wheel 8 each furnished with the handle.

5 The cabin or room may be furnished with berths and a wireless installation.

The top of the cabin or room may also be arranged to carry one or more lifeboats 10 and have masts and anchors.

I claim:

1. A ship's deck room or cabin fitting of the type hereinbefore specified, comprising a series of screw-threaded rotary spindles 15 extending through each end wall of the deck house or cabin in the direction of the ship's side bulwarks, means secured to the inner end of each of said spindles for rotating same, sockets secured to the inner side of 20 the bulwarks or the deck in which the outer end of said spindles are adapted to engage to secure said house or cabin to the ship and permit of rapidly detaching same for floating on the water, for the purpose specified.

25 2. In a ship's deck room or cabin fitting of the type claimed in claim 1, a second series of screw-threaded rotary spindles located in said end walls above said first series 30 of spindles, a cover dependingly hinged to

the outside of each of said wall ends with lower end overlapping the top of the bulwark, and a swivel nut carried by said lower end in which the outer end of said spindles engage, for the purpose set forth. 35

3. A deck cabin or room as claimed in claim 1, comprising at each end two series of screw-threaded spindles located above one another, and a tooth gear which rotatively connects together said two spindles, 40 for the purpose specified.

4. A deck cabin or room as claimed in claim 1, comprising at each end a series of screw-threaded spindles, a cross shaft in connection with each series of said spindles, a screw wheel and a worm secured to each of said spindles and cross shafts, supports on the top of the cabin or room, a horizontal shaft mounted in each of said supports, means for rotating said horizontal 45 shafts and means for transmitting rotary motion to said cross shafts for the purpose specified.

Signed at Manchester, England, this 11th day of July, 1919.

PATRICK CHURCHILL.
